UNITED STATES PATENT OFFICE

90,530

DESIGN FOR A TEXTILE FABRIC

Ernest A. Harrell, New York, N. Y., assignor to Levin-Forman Corporation, New York, N. Y., a Corporation of New York

Application June 15, 1933. Serial No. 48,404

Term of patent 3½ years

To all whom it may concern:

Be it known that I, ERNEST A. HARRELL, a citizen of United States, residing at the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design. The design as shown is one including a selvage. This selvage is shown at the bottom of the drawing.

I claim:

The ornamental design for a textile fabric, substantially as shown and described.

ERNEST A. HARRELL.
